UNITED STATES PATENT OFFICE.

FRED E. SUTTERFIELD, OF FLAT RIVER, MISSOURI.

SHELL.

1,243,641.

Specification of Letters Patent. Patented Oct. 16, 1917.

Application filed, March 13, 1917. Serial No. 154,603.

To all whom it may concern:

Be it known that I, FRED E. SUTTERFIELD, a citizen of the United States, residing at Flat River, in the county of Saint Francois 5 and State of Missouri, have invented new and useful Improvements in Shells, of which the following is a specification.

This invention relates to ammunition, and more particularly to explosive shells; and 10 the object of the same is to provide the shell with means for exploding its charge on impact and means for preventing accidental explosion by impact in case the shell is dropped or otherwise roughly handled before it has been fired from the gun.

In carrying out this object the invention consists in the provision of sparking devices actuated by a battery stored within the shell and connected by a normally broken circuit, 20 and within the break thereof is a circuit closer standing normally open and which can be only closed and is automatically closed by the indentation of the rear end plate of the shell which is purposely made 25 pliable so that it is bent by the force of the firing charge within the gun.

One successful means for carrying out this idea is set forth in the following specification and claims and shown in the drawings, wherein—

Figure 1 is a central longitudinal sectional view of the shell complete,

Fig. 2 is a cross-section on line 2—2 of Fig. 1.

The shell comprises a casing 1, whose body and point are preferably integral but the rear end is open, and this end is covered by a rear end plate 2, which is of pliable metal so that it shall be indented as shown 35 in the dotted lines in Fig. 1, when the shell is fired from the gun and by impact of the explosion of the charge which so fires or projects it. Within the shell just forward 40 of said end plate is a spider 3, carrying an axial guide 4, and forward of the latter is a transverse partition 5. This partition closes the rear end of a tube 6, held within 45 the shell and preferably concentric therewith by means of braces 7, said tube defining a battery chamber 8, whose forward end 50 may well be closed as at 9. The charge of explosive is disposed within the annular chamber surrounding the tube as indicated.

Within the battery chamber is a source 55 of electricity herein shown as made up of two batteries 10 and 11, and a spark coil 12,

all of which are connected up in series. If the batteries are of the dry-cell type their side terminals may be removed and the center terminal of the one indicated as at 13, 60 placed in electrical contact with the bottom of the next battery and the central terminal of the forward battery connected as at 14 with one end of the spark coil. The latter may or may not be used but I prefer to employ it in order to produce a decided spark so that the charge of the explosive will be exploded without fail. For this purpose I employ sparking devices made up of two elements which are normally out of contact. 65 One element is herein shown as a collar fastened on the stem 16 of a plunger which is slidably mounted in guides 17 at the front end of the casing and in the front end 9 of the tube, and whose head 18 stands normally 70 beyond the point of the casing so that when it strikes an object it is driven inward by impact; and the rear end of said stem is electrically connected as at 19 with the forward end of the coil 12. The other element 75 of the sparking device is a contact point or finger 20 carried by and insulated from a bracket 21, mounted on some fixed point of the casing or tube, and this finger stands in such position that when the plunger and 80 collar are driven to the rear by impact, a wiping contact is made between the two elements and a decided spark is produced. An insulated wire 22 leads from the finger 85 back through the shell and is adapted for 90 connection with the lower end of the rear-most battery end so as to form a complete circuit when the plunger is driven inward as stated.

With the parts constructed as thus far described, there is of course danger that while the shell is being handled preparatory to placing it in the gun and firing it, through some carelessness or accident it may be dropped; and if it should fall on the point 95 so that the head of the plunger strikes the ground, or if the accident be one which delivers a blow on the head 18, the sparking device will be energized and the shell exploded, to the serious injury and possible death of those who are near. My invention 100 contemplates the provision of means for safe-guarding against accidents of this character, which means may properly be stated 105 as consisting of breaking the circuit and inserting a circuit breaker in such break, and closing the circuit breaker and circuit 110

automatically only when the shell is fired. This safety device renders it obviously impossible to explode the shell prematurely, because impact on the head of the plunger 5 will not actuate the sparking devices unless and until the circuit is a closed one.

Mounted on the rear end of the rearmost battery is a contact 25, constituting one element of said circuit closer. Slidably mounted in the guide 4 of the spider 3 is the stem 26 of another plunger to which the wire 22 is connected and the inner end of the stem is normally spaced slightly from the contact 25 and constitutes the other element of 10 the circuit closer. The head 27, of the said plunger is connected with or rests against the center of the pliable end plate 2. With this construction, when the end plate is indented at the time the shell is fired from the 15 gun, the plunger is driven inward within the guide 4 and its inner end contacts with the element 25 so that the circuit is no longer broken, excepting that as yet it is interrupted at the point where the spark is to be 20 formed. But as the end plate is purposely so heavy that it can not be indented by hand or accident or in any way excepting by the 25 firing of the shell, it will be clear that the circuit remains a broken one up to the moment when the shell is projected from the gun.

I do not wish to be limited strictly to the details mentioned. Obviously the structure of the shell is immaterial so long as it possesses 30 the features above described. Obviously also, the source of electricity may be any which will produce a suitable spark. Other additions and changes may be made as the necessities of the case demand.

40 What I claim as new is:—

1. A shell comprising a casing, a tube therein defining a chamber, an explosive around the tube, a partition within the casing and across the end of the tube, said partition having a guide opposite the chamber, and a pliable plate closing the rear end of the casing; combined with a battery with the chamber, sparking points whereof one is connected to said battery, a plunger attached to 45 said end plate of the casing and extending thence through said guide with its inner end adjacent the battery whereby it is thrown into electric contact therewith by the firing of the shell, and electrical connections between said plunger and the other spark point.

50 2. A shell comprising a casing, a tube

therein closed at its front end and defining a chamber, an explosive around the tube, a source of electric energy within said chamber, a plunger whose stem is movably mounted through the front end of the casing and front end of the tube, whose inner end is connected with said source and whose outer end carries a head standing normally beyond the shell-casing, spark-producing elements whereof one is connected with said plunger, and a wire leading from the other to the rear end of the casing; combined with normally open circuit-closing mechanism between said wire and the rear end of said source, and means for closing said mechanism by impact due to firing the shell.

3. A shell comprising a casing, a tube therein closed at its front end and defining a chamber, an explosive around the tube, a source of electric energy within said chamber, a plunger movably mounted through the front end of the casing and front end of the tube, and whose inner end is connected with said source, spark-producing elements whereof one is connected with said plunger, and a wire leading from the other to the rear end of the casing; combined with a normally open circuit closer between said wire and the rear end of said source, and a pliable plate across the rear end of the shell indented by impact when the shell is fired and adapted to actuate said circuit closer when so indented.

4. A shell comprising a casing, a tube therein closed at its front end and defining a chamber, a partition within the casing across the rear end of the tube, an explosive charge within the casing around the tube, and a source of electric energy within the chamber; combined with a plunger movably mounted through the front end of the casing and tube with its inner end connected with said source, spark-producing elements outside said tube within the casing and whereof one is connected with said plunger, a wire leading from the other, a pliable plate closing the rear end of the casing, a guide within the latter adjacent said plate, and a plunger attached to the plate and passing through said guide and partition and into the rear end of the tube and adapted to make contact with said source when the plate is indented by the firing of the shell, said wire being connected with this plunger.

In testimony whereof I affix my signature.

FRED E. SUTTERFIELD.
